UNITED STATES PATENT OFFICE.

HAROLD RAY KELSEY AND RALPH JOHN KELSEY, OF POUND, WISCONSIN.

DESIGN FOR A CASING FOR AN ELECTRIC FAN.

58,765.

Specification for Design.

Patented Aug. 30, 1921.

Application filed January 19, 1921. Serial No. 438,454. Term of patent 3½ years.

To all whom it may concern:

Be it known that we, HAROLD RAY KELSEY and RALPH JOHN KELSEY, citizens of the United States, residing at Pound, in the county of Marinette and State of Wisconsin, have invented a new, original, and ornamental Design for a Casing for an Electric Fan, of which the following is a specification, reference being had to the accompanying drawings, forming part thereof.

Figure 1 is an elevational view, and

Fig. 2 is a top plan view of an electric fan, showing our new design.

We claim:

The ornamental design for a casing for an electric fan as shown.

HAROLD RAY KELSEY.
RALPH JOHN KELSEY.
